UNITED STATES PATENT OFFICE.

WILLIAM J. BAUMBERGER, OF DAVENPORT, IOWA, ASSIGNOR TO MICRO MACHINE COMPANY, OF BETTENDORF, IOWA, A CORPORATION OF IOWA.

GRINDING MACHINE.

Application filed June 28, 1923. Serial No. 648,238.

The object of the invention is to provide a gear box assembly and control therefor adapted particularly for reciprocating a work-carrying table on grinding machines and the like, wherein the driving means is quickly reversed, and wherein movement of the table will move said means to neutral position upon failure of parts of the reversing mechanism especially a spring or springs employed for quickly completing the reversing movement, whereby injury to the work will be avoided.

Briefly, the invention resides in a power driven reversing mechanism for reciprocating the table which includes a clutch member shiftable for reversing the movement of a train of gears, whereby the direction of movement of the work-carrying table or bed is reversed, said clutch member being shiftable by the table in its movements, the table engaging an arm which is slidably connected with the clutch member to provide a limited amount of lost motion between the arm and the member during initial movement of the arm, a spring being employed for quickly completing movement of the arm in either direction after the arm is moved slightly past dead center by the moving table, whereby the clutch member is quickly shifted.

Another feature of the invention consists in the provision of means whereby, if the spring breaks, movement of the table will continue the movement of the arm until the clutch member is drawn to neutral position, whereupon movement of the table will cease. The invention also includes a second clutch, preferably a friction clutch, set into the gear train, the friction clutch being manually disengageable, whereby a hand wheel or the like may be actuated for moving a portion of the gear train for rough adjustment of the table.

In the accompanying drawings, wherein one embodiment of the invention is disclosed by way of illustration,

Fig. 1 is a section on line 1—1 of Fig. 2 showing in side elevation the assembly within the gear box, portions of certain gears being broken away.

Fig. 2 is a top plan view of the mechanism shown in Fig. 1 with the cover removed,

viewed as indicated by the arrows 2 in Fig. 1.

Fig. 3 is a vertical cross section taken on the line 3—3 of Fig. 1. 55

Fig. 4 is a section taken approximately on the line 4—4 of Fig. 1 showing the mounting of the clutch shifting arm, the gearing in the casing being omitted.

Fig. 5 is a sectional detail showing the 60 adjustable pin carried in the upper end of the clutch-shifting arm.

Fig. 6 is a diagrammatic side elevation showing the arrangement of the present gear box with relation to the parts of a grinding 65 machine.

Fig. 7 is a sectional detail view showing the connection between the actuating arm and the shiftable clutch member.

As seen in Figs. 3 and 6, a work-carrying 70 table or bed 10 is mounted for reciprocation upon a frame or base 12 having at one end a housing 14 containing suitable mechanism for driving the gear assembly of the present invention and for also driving a 75 shaft 15 projecting from said housing and carrying a grinding wheel 16 adapted to operate upon a piece of work supported in any suitable manner upon a work-carrier 18 secured to the table or bed 10. 80

For reversing the table actuating mechanism the table 10 is provided with spaced laterally projecting engaging studs or blocks 20 on one side thereof which are adjustable longitudinally of the table and are 85 adapted to engage a suitable controller arm for causing the shifting of the reversing clutch. Mounted on a horizontal pivot 21 at the bottom of the gear box B is an arm 22 which projects through the top of the 90 gear box adjacent the side edge of the table 10. The upper end of the arm 22 is between the two blocks 20 just outside the path of movement thereof, and carries at its upper end a horizontally disposed sleeve 95 23 in which is a slidably mounted pin 24 which is adapted to be adjusted to a position in which the inner end thereof is in the path of movement of the blocks, so that the arm 22 will be actuated by the blocks 100 during reciprocation of the table 10.

The sleeve 23 projects outwardly from the

arm 22 and has a threaded inner end which is screwed into an opening in the upper end of the arm 22. The pin 24 is held in adjusted position within the sleeve 23 by means of a bowed leaf spring 25 positioned within a longitudinal groove in the pin 24 and bearing against the inner surface of the sleeve 23. For limiting the longitudinal movement of the pin 24, the sleeve 23 carries a set 10 screw 26, the inner end of which projects into a longitudinal groove in the pin 24. Thus said pin 24 may be projected into the path of the stops 20 as shown, or may be withdrawn therefrom when actuation of 15 arm 22 is not desired.

Gear box B is bolted at 28 to the base 12 in position for actuation of said arm 22 by said stops 20, and a suitably driven power shaft 30 leads to said box, the shaft 30 being 20 driven through a clutch 30' by means of which the shaft 30 may be connected to or disconnected from the source of power. Within the gear box B the power shaft 30 has a clutch member 32 splined thereon, 25 which is shiftable into driving engagement with either of the two oppositely facing beveled pinions 33 and 34 which are loose on the shaft 30, or is movable into neutral position, as shown in Fig. 2, by means of a 30 yoke 35 pivoted at 35' to the back wall of the gear box B, said yoke 35 being operable from the arm 22 by means of a connecting link or rod 36.

The connecting rod 36 is supported in 35 horizontal position for longitudinal sliding movement directly over the shaft 30 in a bearing block 36^a carried upon the top of the end bearing of the shaft 30. The connecting rod 36 has a longitudinally extending 40 slot 36^b at its forward end which receives a vertical pin 36^c carried by the outer end of the yoke 35, the movement of the pin 36^c in the slot being limited by stop members 36^d which are detachably and slidably mounted 45 at opposite ends of the slot, the stop members 36^d being adjustable to vary the amount of lost motion between the rod 36 and yoke 35 by means of adjusting screws 36^e which serve to properly position the stop members 36^d with respect to the yoke 35 as well as 50 to vary the length of the slot. At its rear end the rod 36 has an enlargement 36^f which has a flat outer face in which there is a vertical groove 36^g into which extends a pin 37 carried by the outer end of a forwardly 55 extending portion 37^a of the arm 22. The pin and groove connection between the rod 36 and arm 22 provides the necessary relative movement to permit the rod 36 to be 60 shifted back and forth by the arm.

In Fig. 7 the gears 33 and 34 may have sleeves thereon for yieldingly engaging with the jaw clutch member 32 so that the clutch teeth of the member 32, if not in proper 65 alignment with the notches in the clutch

member of the gear at the instant of engagement, will snap into engagement as soon as the shaft rotates sufficiently to align the teeth with the notches.

An important feature of the present invention consists in the provision of a spring actuator operable to move the clutch members into engagement and so connected to the clutch shifting mechanism that in the event the spring actuator becomes ineffective 70 the clutch element controlling the actuation of the table will always be stopped in neutral position. To accomplish this result, an actuating spring 40 is so connected to the arm 22 that immediately after movement of 75 the arm in either direction from neutral position by one of the blocks 20 on the table, the spring 40 will act upon the arm 22 to continue the movement of the arm at a more rapid rate and snap the clutch element 80 85 90 into engagement with the gear toward which it is moving. The spiral spring 40 is connected at its lower end with a vertically disposed eye bolt 41 connected to the bottom of the gear box B in front of the arm 22 and in vertical alignment with the pivot 21 of the arm. The upper end of the spring 40 is connected to an eccentric pin 42 on a disk 43 fixed to the outer end of a shaft 44 which is journaled in a bearing boss 44' on the 95 rear wall of the gear box behind the lever 22. The shaft 44 extends through an elongated transverse slot in the arm 22 and has a 100 pinion 45 fixed thereon which meshes with rack teeth 46 formed in the lower edge of the slot.

When the arm 22 is in vertical position the clutch element 32 is in neutral position and the pin 42 is positioned directly over the shaft 44 so that the pin 42 is at dead center and the spring exerts no turning force on the disk. However, upon movement of the arm in either direction from vertical position, the disk 42 will be rotated in the direction of movement of the arm through the pinion 45 and rack 46 and the pin 42 will be shifted off center, whereupon the spring 40 will act upon the disk 43 to rapidly turn the shaft 44 and shift the arm 22 through the pinion 45 and rack 46 to engage 105 the clutch element 32 with the gear toward which it is moving. The clutch element 32 will normally be in engagement with one of the gears 33 or 34 so that when the clutch 31 is thrown in the 110 table will be shifted. As the table is shifted, one of the abutments 20 will engage the pin 24 and shift the arm in a direction to disengage the clutch, the slot 36^b permitting the arm to move slightly past neutral position 115 before the clutch is disengaged. As the arm 22 is moved past neutral position, the spring 40 becomes effective and snaps the clutch member 32 into engagement with the opposite gear, reversing the direction of move- 120 125 130

ment of the table, whereupon the operation above described is repeated when the table has moved far enough to bring the other abutment 20 into engagement with the pin 5 24.

However, if spring 40 should be broken or has become too weak so that quick movement of the arm 22 thereby cannot be made to shift the clutch 32 from one pinion to the 10 other, continued movement of the table 10 will gradually move the arm 22 to cause link 36 to move clutch 32 into neutral position as shown in the drawings whereupon the table will stop.

15 In order to close the top of the gear box B a plate 48 is provided which slides in guides 49 with the movements of the arm 22 which projects through said plate 48.

The pinions 33 and 34 engage with a bevel 20 gear 50 which is driven thereby in opposite directions as the clutch 32 drives one and then the other thereof. Gear 50 carries a pinion 54 which drives a gear 55 journaled on a sleeve 56 rotating on a shaft 57, the 25 sleeve 56 being rotated through the medium of a cone clutch 58 keyed on said sleeve 56 and movable to and from engagement with an inner clutch face of gear 55. Sleeve 56 has a pinion 59 fixed thereon which drives gear 60 through the medium of an idler 61, the gear 60 being fixed on a shaft 62 which carries a gear 64 in engagement with a rack 65 on the table 10 for reciprocating the latter. Thus power from the shaft 30 is transmitted to the table 10 to move the same in opposite directions, the direction of drive being reversed by actuation of arm 22 to shift clutch 32 into and from engagement with the pinions 33 and 34 as above described.

In order that the table 10 may be rotated by hand, as for purposes of rough adjustment or the like, a hand wheel 70 fixed to the shaft 57 and a hand wheel 72 threaded on the outer end of sleeve 56 are provided. Wheel 72 engages the inner face of the hub of wheel 70 and the outer face of the bearing for gear 55, so that turning of wheel 72 to cause it to move outwardly on sleeve 56 causes the sleeve and cone clutch 58 to be moved inwardly to disengage clutch 58 from gear 55, the inner end of sleeve 56 having sufficient play at 56' for this purpose. Hand wheel 70 is then free to be rotated for turning the shaft 57 and a pinion 74 fixed thereon; pinion 74 drives idlers 75 and 76 and idler 76 also meshes with the gear 60 for driving the table 10 through the medium of hand wheel 70. When the table has been moved as desired, hand wheel 72 is then returned to cause cone clutch 58 to engage gear 55, so that the table may be automatically reciprocated as herein above described when clutches 30' and 32 are engaged. A removable plate 80 may be provided for easy ac-

cess to spring 40 without disturbing the cover on the gear box B.

Thus, a gear assembly is provided whereby the table 10 may be actuated either by power or by hand, and whereby the moving 70 parts will be placed in neutral position upon failure of the spring 40 during power drive thereby avoiding all possibility of danger to the work on the table.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. In combination, a reciprocable table, 85 a gear drive therefor, a clutch for said gear drive movable to positions for driving the table in opposite directions, a shiftable member having a lost motion connection with said clutch, a rack for actuating said member, a pinion for actuating the rack, said pinion having a relatively stationary axis and means connected with the pinion for causing a quick movement thereof in each direction beyond a dead center position, said 90 shiftable member being actuatable in both directions by said table to cause movement of said pinion to a position of dead center.

2. In combination, a reciprocable table, a gear drive therefor, a clutch for said gear drive movable to positions for driving the table in opposite directions, a shiftable member having a lost motion connection with said clutch, a rack for actuating said member, a pinion for actuating the rack, said 100 pinion having a relatively stationary axis, and spring means eccentrically connected with the pinion for causing movement thereof in each direction beyond a dead center position, said shiftable member being actuatable in both directions by said table to cause movement of said pinion to a position of dead center.

3. In combination, a gear drive, a clutch therefor movable to positions for driving different gears, a movable arm connected with said clutch for shifting the clutch, a rack on said arm, a pinion in engagement with said rack, said pinion having a relatively stationary axis, and a spring eccentrically connected with said pinion for quick movement of the arm beyond dead center.

4. In combination, a reciprocable table, a gear drive therefor, a clutch for said gear drive movable to positions for driving in opposite directions, a slidble member having a lost motion connection with said clutch, a rack operatively connected to said member, a pinion for actuating said rack, said 125

4
pinion having a relatively stationary axis and a spring eccentrically connected with said pinion for causing quick movement thereof beyond dead center, said slideable member being actuatable in both directions by said table to cause movement of said pinion to a position of dead center.

5. In combination, a gear drive, a clutch therefor movable to positions for driving in opposite directions, a swinging arm having a lost motion connection with said clutch for movement of the arm to dead center without shifting the clutch, a rack on said arm, a pinion having a relatively stationary axis engaging said rack, a connection eccentrically connected with said pinion to be at dead center when said arm is at dead center, and a spring engaging said connection to produce quick movement of the arm beyond dead center for quick movement of the clutch.

6. In combination, a gear drive, a clutch therefor movable to neutral position and to positions for driving in opposite directions, a pivoted arm having lost motion connection with the clutch for initial movement of the arm to dead center without movement of the clutch, a spring to complete movement of the arm beyond dead center for movement of the clutch, and a rack and pinion connection between said spring and arm, the attachment of the spring being eccentric and being adapted to be at dead center when the arm is at dead center.

7. In combination, a gear drive, a clutch therefor movable to neutral position and to positions for driving in opposite directions, a pivoted arm having lost motion connection with the clutch for initial movement of the arm to dead center without movement of the clutch, a spring to complete movement of the arm beyond dead center for movement of the clutch, and rack and pinion connection between said spring and arm, the attachment of the spring being eccentric and being adapted to be at dead center when the arm is at dead center, the arm being movable beyond dead center upon failure of the spring in order to shift the clutch to neutral position.

8. In combination, a reciprocable table, a gear drive therefor, a clutch movable to neutral position and to positions for driving in opposite directions, a pivoted arm having a lost motion connection with the clutch for initial movement of the arm by the table without movement of the clutch, a spring to complete movement of the arm beyond

dead center for movement of the clutch from one driving position to the other, and a rack and pinion connection between said arm and spring for quick movement of the clutch, the attachment of the spring to the rack and pinion connection being eccentric and being adapted to be at dead center when said arm is at dead center, the arm being movable beyond dead center by movement of the table upon failure of the spring in order to shift the clutch to neutral position.

9. The combination with a reciprocable table, of means to drive the same comprising a drive gear, a sleeve about which said gear rotates, a clutch member fixed to rotate with the sleeve and movable to and from driving engagement with said gear, gearing driven by said sleeve to actuate said table, a shaft rotatable within the sleeve, hand operable means to rotate the shaft, a pinion on said shaft, gearing operable by said pinion to actuate said table when said clutch is released from the drive gear, and means for moving said clutch into and out of engagement with said gear.

10. In combination, a drive member, a sleeve about which said member rotates, a clutch fixed to rotate with the sleeve and movable to and from driving engagement with said member, driven means actuated from said sleeve, a shaft rotatable within the sleeve, hand operable means to rotate the shaft, means on the shaft to drive said driven means when said clutch is released from said drive member, and a hand operated device engaging said sleeve for shifting said clutch through the medium of said sleeve.

11. In combination, a drive member, a sleeve about which said member rotates, a clutch fixed to rotate with the sleeve and movable to and from driving engagement with said member, driven means actuated from said sleeve, a shaft rotatable within the sleeve, hand operable means to rotate the shaft, means on the shaft to drive said driven means when said clutch is released from said drive member, and a hand operated device engaging said sleeve for shifting said clutch through the medium of said sleeve, the hand operated device for the sleeve being disposed between the drive member and the hand operable means for the shaft.

In testimony whereof, I hereunto affix my signature.

WILLIAM J. BAUMBERGER.
